GRINDING DISK

Ingle R. Shue, Beloit, Wis., assignor to Gardner
Machine Company, Beloit, Wis., a corporation of
Illinois

Application August 10, 1931, Serial No. 556,050

15 Claims. (Cl. 51—209)

The present application is a continuation in part of applicant's copending application, Serial No. 539,859, filed May 25, 1931.

The invention relates generally to grinding wheels, and more particularly to wheels of the disk type.

10 Wheels of this type are usually used in a machine operating at relatively high speeds which create centrifugal forces of considerable magnitude. The wheels must therefore have sufficient strength to withstand such forces. The abrading material is made in different grades for different classes of work, and the strength of the abrading material varies with the different grades. 15 It is preferable that some means be provided for strengthening disks of any grade but especially for disks of a soft grade.

20 The general object of the invention is to provide a new and improved grinding disk which may be made in any desired grade of hardness, and which has great strength not solely dependent upon the grade of abrading material used.

25 More specifically, the object is to provide a grinding disk of this character comprising two layers of molded material, one being an abrading material of any desired grade, while the other is a material of great strength intimately connected to the layer of abrading material.

30 Another object is to provide a grinding disk of this character, in the rear or strengthening layer of which are embedded reinforcing and securing means for attaching the disk to a supporting wheel.

35 A further object is to provide a narrow-faced annular form of disk comprising two layers of the above-mentioned character, wherein the rear or strengthening layer not only underlies the layer of abrading material but also extends inwardly beyond said abrading layer with reinforcing and securing means embedded in said inwardly extending portion.

40 Other objects and advantages will become apparent from the following description taken in connection with the accompanying drawing, in which:

45 Figure 1 is a perspective view, partially broken away, of a supporting wheel and grinding disk assembly embodying the features of the invention.

50 Fig. 2 is a perspective view similar to Fig. 1 but of a modified form of disk.

55 Fig. 3 is an enlarged fragmentary sectional view of both forms of disks.

60 In a grinding disk embodying the features of the invention, two layers of molded material in-

timately attached to each other are provided. One layer, comprising the portion available for use in grinding, is made of abrading material of any desired grade suited to the work to be done. The other layer is made of molded material having relatively great strength and forming the rear part of the disk.

65 As shown in the drawing, a supporting wheel 10 is provided which is adapted to be secured to a driving means, as by screws (not shown) passing through holes 11 and adapted to be threaded into a flange on the driving spindle of a grinding machine (not shown). Positioned with its rear face against the supporting wheel 10 is a grinding disk, indicated generally at 12.

70 The preferred embodiment of the grinding disk 12, shown in Fig. 1, comprises a layer 13 constituting the front portion of the disk and made of molded abrading material, usually comprising abrasive grains and a bond of any desired grade suitable for the class of work the disk is expected to do. Since such material often lacks sufficient strength, it is desirable to provide some strengthening means in order that the disk may withstand the large centrifugal forces arising when the disk is rotated at relatively high speeds.

75 To strengthen the layer 13 and thus prevent cracking thereof due to said forces, a second layer 14 of molded material is formed at the rear of the layer 13 and is intimately connected therewith to prevent separation thereof. The rear layer 14 is made of any suitable molded material having great tensile strength. Such material may be bonding material alone or with a suitable proportion of granular, fibrous or other suitable material mixed therein. Preferably a metallic reinforcement is molded in the rear layer 14 but if none is used this layer should be composed of material having inherently greater tensile strength than the front abrasive layer 13 so as to withstand the centrifugal forces set up in the disk when rotated at high speed.

80 To give added strength to the disk, reinforcing means is preferably used. As illustrated herein the reinforcing means comprises a wire mesh 15, although expanded metal or other foraminous material may be used in its stead. The wire mesh 15 is preferably embedded in the rear face of the rear layer 14 and is coextensive with said layer.

85 The means for securing the grinding disk 12 to the supporting wheel 10 comprises pairs of cooperating members, one embedded in the disk and the other removable therefrom. As illus-

trated herein, the embedded members comprise a plurality of nuts 16 positioned in a predetermined arrangement relative to the face area of the disk comprising a plurality of circular, 5 radially spaced rows, and embedded in the rear layer 14. Threaded into each nut 16 is a screw 17 constituting the removable member and extending through the supporting wheel 10 with its head preferably countersunk in the rear face 10 of the supporting wheel. The nuts 16 bear against the inner face of the wire mesh and clamp the mesh securely against the supporting wheel so that the rear layer 14 receives all of the centrifugal and torsional stresses set up in 15 the disk as a whole. The mesh preferably is at least coextensive with the areas bounded by the circles of the inner and outer rows of nuts. The form of securing means illustrated herein is merely exemplary, and it is contemplated that 20 other forms may be used.

Since the disk can be used for grinding purposes only down to the nuts 16, the line of division between the layers 13 and 14 may lie flush with the inner face of the nuts 16 as is clearly 25 shown in Fig. 3. Thus, the layer 13 occupies that portion of the disk which is available for grinding purposes while the layer 14, which gives strength to the disk, occupies that portion of the disk which is not available for grinding purposes. 30 In many disks, only the portion adjacent the periphery is used. For this class of work, the grinding disk may be in the form of an annulus 20, as shown in Fig. 1. However, the internal stress in the disk due to centrifugal forces re- 35 mains relatively large. To give the disk sufficient strength to withstand such forces, the inner or rear layer, formed of material having greater strength than the annulus 20 which is made of abrading material, not only underlies the entire 40 area of the annulus but also extends radially inwardly therefrom, as shown at 21. Thus, the rear layer is of maximum size for a given diameter of disk.

This form of disk may also include a plurality of nuts, similar to those shown in Fig. 2, 45 for securing the grinding disk to the supporting wheel 10, and a reinforcing means such as a wire mesh to give additional strength to the disk. The nuts and wire mesh are embedded in the rear layer, 50 some of the nuts being positioned in the inwardly extending portion 21 of the rear layer in order that the stresses set up will be distributed over the whole area of the rear layer.

From the above description, it will be apparent that I have provided a grinding disk in which the front or abrading portion may be made in any desired grade of hardness, and which is strengthened by a rear layer of molded material having great tensile strength to resist the stresses 55 due to centrifugal force. The rear layer has embedded therein the means for securing the disk to a supporting wheel and preferably also has reinforcing means to give additional strength to the disk. The rear layer, where both layers 60 are in the form of annuli, may also extend inwardly beyond the front layer of abrading material with certain of the securing members embedded in the inwardly extending portion.

I claim as my invention:—

70 1. A grinding disk comprising, in combination, a layer of moulded abrading material constituting the front portion of the disk, a second layer intimately attached to the rear face of said first layer and made of a relatively stronger moulded material, reinforcing means embedded in said

second layer and coextensive therewith, and securing means embedded in said second layer.

2. A grinding disk comprising, in combination, a layer of moulded abrading material constituting the front portion of the disk, a second layer intimately attached to the rear face of said first layer and made of a relatively stronger moulded material, and reinforcing and securing means embedded in said second layer, said second layer having a thickness equal to that of said means.

3. A grinding disk comprising, in combination, a layer of moulded abrading material, a second layer of relatively stronger moulded material, and reinforcing and securing means embedded in said second layer, said second layer comprising that part of the disk rendered unavailable for grinding purposes by said means.

4. A grinding disk comprising, in combination, a layer of moulded abrading material, a second layer of relatively stronger moulded material, reinforcing means embedded in the outer face of said second layer, and a plurality of securing means embedded in said second layer against said reinforcing means, the inner faces of said securing means lying flush with the inner face 100 of said second layer.

5. A grinding disk comprising, in combination, a front layer of moulded abrading material, a rear layer of relatively stronger moulded material, a wire mesh embedded in the rear face of the rear layer, and a plurality of nuts embedded in said rear layer and bearing against the front face of said mesh, the front faces of said nuts lying flush with the front face of said rear layer.

6. A grinding disk comprising a plurality of 110 layers of different compositions, and means moulded in the rearmost layer for reinforcing the latter and for securing the disk as a whole to a supporting wheel.

7. A grinding disk adapted to be secured to a 115 supporting wheel comprising, in combination, two concentric annular layers, the first layer constituting the rear portion of the disk and having reinforcing and securing means molded therein and constructed for securing the disk as a whole 120 to said supporting wheel, and the second layer constituting the front portion of the disk and having a larger internal diameter than said first layer.

8. A grinding disk adapted to be secured to a 125 supporting wheel comprising, in combination, two concentric annular layers, the first layer constituting the rear portion of the disk and having reinforcing means and securing means molded therein for securing the grinding disk as a 130 whole to said supporting wheel, the reinforcing means being coextensive with said first layer, and the second layer constituting the front portion of the disk and having a larger internal diameter than said first layer.

9. A grinding disk adapted to be secured to a supporting wheel comprising, in combination, two concentric annular layers, the first layer constituting the rear portion of the disk and having reinforcing and securing means embedded therein, said first layer having a thickness equal to the thickness of the reinforcing and securing means, and the second layer constituting the front portion of the disk and having a larger internal diameter than said first layer.

10. A grinding disk adapted to be secured to a supporting wheel comprising, in combination, two concentric annular layers, the first layer constituting the front portion of said disk, and the second layer being made of molded material and 150

- constituting the rear portion of the disk and having a smaller internal diameter than said first layer, said second layer having a plurality of securing means embedded therein for attaching the disk to the supporting wheel with certain of said securing means located in the part of said second layer which extends inwardly beyond said first layer. 5
11. A grinding disk adapted to be secured to a supporting wheel comprising, in combination, two concentric annular layers, the first layer constituting the front portion of said disk, and the second layer constituting the rear portion of the disk and having a smaller internal diameter than said first layer, said second layer having a wire mesh embedded therein and a plurality of nuts for clamping said disk to the supporting wheel bearing against the wire mesh with certain of said nuts located in the part of said second layer which 10 extends inwardly beyond said first layer.
12. A grinding disk adapted to be secured to a supporting wheel comprising, in combination, two concentric annular layers, the first layer constituting the front portion of said disk, and the second layer constituting the rear portion of the disk and having a smaller internal diameter than said first layer, said second layer having a wire mesh embedded in the rear face thereof coextensive therewith and having a plurality of nuts for 15 securing the disk to the supporting wheel and spread over the front face of said mesh in a predetermined arrangement.
13. A grinding wheel comprising, in combination, a supporting wheel, a grinding disk secured 20 to said supporting wheel and comprising a reinforcing sheet of wire mesh positioned adjacent the rear face of said disk, a plurality of nuts scattered about the front face of said mesh and bearing against said mesh, a rear layer of bonded granular material in which said nuts and mesh are embedded with the front face of said rear layer flush with the front face of said nuts whereby said rear layer constitutes that portion of the thickness of the disk which said nuts and mesh occupy, and a front layer of bonded abrasive material intimately connected to the rear layer, and a plurality of screws, one for each nut, extending through the supporting wheel and threaded into said nuts. 25
14. A grinding disk comprising, in combination, a layer of molded abrading material constituting the front portion of the disk, a second layer made of molded material and intimately attached to the rear face of said first layer, reinforcing means molded in said second layer, and securing means molded in said second layer for securing the grinding disk as a whole to a supporting wheel. 30
15. A grinding disk comprising, in combination, a layer of molded abrading material constituting the front portion of the disk, a second layer made of molded material and intimately attached to the rear face of said first layer, a plurality of circular, radially spaced rows of securing members molded in said second layer for securing the grinding disk as a whole to a supporting wheel, and reinforcing means molded in said second layer and being at least coextensive with the area bounded by the circles of the inner and outer rows of securing members. 35
